UNITED STATES PATENT OFFICE

159,955

PENDANT OR SIMILAR ARTICLE

Michael Chernow, New York, N. Y.

Application March 10, 1950, Serial No. 8,445

Term of patent 7 years

(Cl. D45—17)

To all whom it may concern:

Be it known that I, Michael Chernow, a citizen of the United States and residing at New York, in the county of New York and State of New York, have invented a new, original, and ornamental Design for a Pendant or Similar Article, of which the following is a specification; reference being had to the accompanying drawing, forming part thereof, and in which

Fig. 1 is a perspective view of the pendant or similar article showing my new design,

Fig. 2 is a rear view thereof,

Fig. 3 is a side view thereof, and

Fig. 4 is a front view thereof.

I claim:

The ornamental design for a pendant or similar article, substantially as shown.

MICHAEL CHERNOW.
